SHOE ORNAMENT

Application filed August 1, 1930. Serial No. 472,309.

This invention relates to certain improvements in shoe ornaments, or imitation buckles in which a metal base is combined with leather or similar sheet material to produce an ornamental appearance.

5 The objects of our invention are to provide a form of metal base for a shoe ornament which will enable sheet material, such as leather, to be cut into strips and arranged thereon so as to produce an ornamental appearance, and which, at the same time may be produced at a minimum expense, and will be durable and of a permanent nature.

10 We accomplish these objects by means of the construction hereinafter described and as illustrated in the accompanying drawing, in which:

Fig. 1 is a front elevation of a shoe ornament embodying the invention.

15 Fig. 2 is a sectional view on an enlarged scale, taken at line 2—2 of Fig. 1.

Fig. 3 is a sectional view, at line 3—3 of Fig. 1 and

20 Fig. 4 is an elevation of the rear side of the ornament, partly constructed.

25 According to our invention, a metal plate *a* is provided which is die cut out of thin sheet metal, and which, for the purposes for which it is used, must have a suitable ornamental finish.

30 At the time the stamping, or dieing operation is performed, the plate is indented from its back side to form a series of embossed, parallel ribs *b* on its front, or face side, which extend from its top to its bottom edges. 35 Each rib is also extended beyond the edge at each end, forming projections *b'*. Transverse grooves are thus provided on the face side of the plate which terminate in notches at each edge.

40 Strips *c* of thin sheet material, preferably leather, are provided, which are equal in width to the distances between the ribs, and are of a thickness preferably slightly less than the height of the ribs *b* or the depth of the grooves formed therebetween. One of said strips is singly fitted into each groove of the plate, so that their edges are closely engaged with the ribs at each side thereof and the end portions of the strips are bent

about the edges of the plate between the projections *b'* and laid against the back side thereof, where they are securely attached by an adhesive, or other suitable means, as indicated in Fig. 4. The thickness of the leather 55 is preferably slightly less than the depth of the grooves and end notches, so that the ribs project slightly beyond the surfaces of the leather strips, at the front side, and at the edges of the plate, as shown in Figs. 2 and 4. 60

In practice the strips *c* are formed of leather having a variety of finishes, so that, by suitably arranging the strips, various ornamental effects may be produced.

As thus arranged the ribs and projections 65 *b*, *b'* have an ornamental, as well as a mechanical effect, in connection with the leather strips, in that they provide a finish for the edges of the strips and greatly enhancing the ornamental effect, the metal having an ornamental finish, as well as the leather. Also they act to hold the strips securely in position at the front and edges of the plate, preventing all possibility of one strip riding on those next adjacent. The ribs and projections also 70 greatly facilitate the work of placing the strips in position, as they hold the strips in the desired positions until secured.

Also when the ornament is worn on the shoe, practically all possibility of displacement of the strips is prevented.

While any thin sheet material may be employed in lieu of leather, with which the advantages of the construction would be secured, the advantages are particularly great 85 when strips are employed which do not have a selvage edge, as in the case of leather strips, with which the full advantages of the invention are secured.

It will be apparent that the form of the 90 strips and the form of the ribs which will correspond to the edges thereof, may be varied without departing from the invention.

We claim:

1. A shoe ornament comprising a metal 95 plate having a series of projecting ribs extending transversely of the front side thereof from edge to edge and providing shallow grooves therebetween, and ornament strips of sheet material disposed in said grooves 100

with their edges fitted against the sides of said ribs and their end portions extending about the edges of the plate and secured to the back side thereof.

- 5 2. A shoe ornament comprising a metal plate having a series of ribs extending transversely of the front side thereof and projecting beyond the edges of the plate at the ends of said ribs, and a corresponding series
10 of strips of flexible sheet material disposed on said plate and closely fitted between said ribs, and having their end portions bent about the edges of the plate and secured to the back side thereof.
- 15 3. A shoe ornament comprising a metal plate having a series of ribs extending transversely of the front side thereof and projecting beyond the edges of the plate at the ends of said ribs, and a corresponding series
20 of strips of flexible sheet material of less thickness than the height of said ribs and projections, and disposed between said ribs and projections with their edges closely engaged therewith, the end portions of the
25 strips being bent about the edges of the plate and secured at the rear side thereof.

In testimony whereof, we have signed our names to this specification.

GEORGE H. PULSIFER.

30 WARREN L. DELANEY.
